CLAIM

The ornamental design for control panel, as shown and described.

DESCRIPTION

FIG. 1 is a top view of the control panel;
FIG. 2 is a left side view of the control panel;
FIG. 3 is a right side view of the control panel;
FIG. 4 is a rear view of the control panel;
FIG. 5 is a front view of the control panel;
FIG. 6 is a bottom view of the control panel; and,
FIG. 7 is a perspective view of the top, rear, and right side of the control panel.

The broken lines in FIGS. 1-7 show portions of the control panel that form no part of the claimed design.

1 Claim, 4 Drawing Sheets
